UNITED STATES PATENT OFFICE.

GEORGE H. RICE, OF HONOLULU, TERRITORY OF HAWAII.

SAFETY CRANKING DEVICE.

1,199,612.

Specification of Letters Patent. Patented Sept. 26, 1916.

Application filed August 7, 1915. Serial No. 44,306.

To all whom it may concern:

Be it known that I, GEORGE H. RICE, a citizen of the United States, and a resident of Honolulu, Territory of Hawaii, have invented a new and Improved Safety Cranking Device, of which the following is a full, clear, and exact description.

The object of the invention is to provide a new and improved safety cranking device for use on shafts of internal combustion engines of automobiles, motor boats and other vehicles, and arranged to permit the operator to safely turn the engine shaft without danger of injury to the operator on back firing of the engine.

In order to accomplish the desired result, use is made of a cranking shaft adapted to be connected by a soft clutch member with a clutch member of the engine shaft to allow of turning the latter on turning the cranking shaft, the said soft metal clutch member being adapted to be shorn off on a return movement of the engine shaft to disconnect the cranking shaft and the engine shaft.

A practical embodiment of the invention is represented in the accompanying drawings forming a part of this specification, in which similar characters of reference indicate corresponding parts in all the views.

Figure 1 is a sectional side elevation of the safety cranking device as applied and with the parts in normal non-engaged position, the section being on the line 1—1 of Fig. 2; Fig. 2 is a sectional front view of the same on the line 2—2 of Fig. 1; Fig. 3 is an enlarged sectional side elevation of the cranking device with the parts in position for turning the engine shaft on turning the cranking shaft, the section being on the line 3—3 of Fig. 5; Fig. 4 is an end view of the socket on the cranking shaft; and Fig. 5 is an end view of the engine shaft.

The cranking shaft A is mounted to turn and to slide in the direction of its axis on the engine frame B, and the said cranking shaft A is in axial alinement with the engine shaft C. The outer end of the cranking shaft A is provided with a handle D and the said cranking shaft is normally held in outermost position by a spring E coiled around the shaft A and resting with one end on the frame B and pressing with its other end on the handle D.

The inner end of the cranking shaft A is provided with a socket F carrying a screw

or a pin G of soft metal such as copper or other annealed metal, and the inner end of this pin G is adapted to engage one of a series of shoulders H formed on the end of the engine shaft C. The pin G and the corresponding shoulder H form clutch members to allow of turning the engine shaft C from the cranking shaft A at the time the latter is rotated and its socket F is engaged with the ends of the shaft C. Now in case of back firing in the engine the shoulder H shears off the inner end of the pin G thus preventing injury to the operator having hold of the handle D for turning the shaft A.

In order to prevent return movement of the shaft A use is made of a ratchet wheel I secured on the cranking shaft A and engaged by one or two dogs J fulcrumed on the frame B and pressed on by springs J' to hold the dogs in engagement with the teeth of the ratchet wheel I. Normally the socket F is out of engagement with the end of the engine shaft C, and in order to guide the pin G into engagement with a shoulder H, use is made of a latch pin K adapted to engage one of a series of recesses F' formed in the inner surface of the socket F. The latch pin K is provided with a head K' pressed on by a spring L and held with the latter in a recess N formed in the engine shaft C next to the shoulders H. The pin K is mounted to slide in a plug O screwing in the wall of the bore N. The latch pin K has beveled sides but a straight front so as to readily engage one of the recesses F' on pushing the cranking shaft A inward, it being understood that the latch pin K registers with one of the recesses F' at the time the pin G is in register with one of the shoulders H.

It is understood that the pin G has sufficient strength to turn the engine shaft C for starting the engine but in case of back firing the reverse movement given to the engine shaft C causes the shoulder H in engagement with the pin G at the time to shear off the latter especially as the cranking shaft A is held against return movement by the pawls J engaging the ratchet wheel I.

Having thus described my invention, I claim as new and desire to secure by Letters Patent:

1. A safety cranking device, comprising a cranking shaft having a socket, a pin of soft metal held on the said socket, a clutch

member on the end of the engine shaft and adapted to be engaged by the said socket and pin to rotate the engine shaft on turning the cranking shaft, the said clutch member being adapted to shear off the said pin on a return movement of the engine shaft, and guiding means for guiding the said socket into position on the end of the engine shaft to cause the pin of the socket to properly engage the clutch member.

2. A safety cranking device, comprising a cranking shaft having a socket, a pin of soft metal held on the said socket, a clutch member on the end of the engine shaft and adapted to be engaged by the said socket and pin to rotate the engine shaft on turning the cranking shaft, the said clutch member being adapted to shear off the said pin on a return movement of the engine shaft, the said socket having a series of recesses, and a spring-pressed latch pin held on the engine shaft and adapted to register with one of

the said recesses at the time the said soft pin is in register with the clutch member.

3. A safety cranking device, comprising a cranking shaft having a socket provided with recesses, a pin of soft metal in the socket, a clutch member on the end of the engine shaft and having shoulders, said clutch member being adapted to enter the socket with a shoulder in engagement with the pin, the shoulder of the clutch member being adapted to shear off said pin on the engine shaft, and a sliding and spring pressed latch pin mounted in the clutch member, said pin having beveled sides and adapted to enter a recess of the socket.

In testimony whereof I have signed my name to this specification in the presence of two subscribing witnesses.

GEORGE H. RICE.
